UNITED STATES PATENT OFFICE.

HARRY CHAS. McCORD, OF BALTIMORE, MARYLAND.

FOLDING CRIB.

1,390,630.

Specification of Letters Patent. Patented Sept. 13, 1921.

Application filed March 15, 1921. Serial No. 452,412.

To all whom it may concern:

Be it known that I, HARRY CHARLES McCORN, a citizen of the United States, residing at Baltimore, in the county of Baltimore and State of Maryland, has invented 5 certain new and useful Improvements in Folding Cribs, of which the following is a specification.

This invention relates to improvements in 10 beds, cribs and the like and has for an object the provisions of a foldable crib of light and durable construction, which may be easily and quickly folded and packed into a small space for storage or transportation, 15 especially adapting the crib for the use of picnic or traveling or camping parties, as well as home use.

Another object of the invention is the provision of a crib in which the bottom, side 20 and end walls are formed of canvas or other washable material, which is removably attached thereto so that the said material may be laundered and kept in a clean and sanitary condition.

Another object is the provision of a crib 25 which includes the above advantages and which, may in addition, be removably secured to the side of a bed so that the latter will act as a support for one side of the 30 crib, while the opposite side is provided with an expandable support which may be adjusted to conform to the height of the bed.

With the above and other objects in view, 35 the invention further includes the following novel features and details of construction, to be hereinafter more fully described, illustrated in the accompanying drawings and pointed out in the appended claims.

In the drawings:—

Figure 1 is a perspective view of a crib 40 embodying the invention and shown set up for use.

Fig. 2 is a top plan view of the same with a portion of the bottom of the crib broken 45 away.

Fig. 3 is a side elevation.

Fig. 4 is a bottom plan view with the pivoted supporting legs shown in section.

Fig. 5 is a top plan view showing the side 50 and end walls folded upon the bottom of the crib preparatory to final folding.

Fig. 6 is a side view showing the manner in which the crib may be compactly folded.

Fig. 7 is a detail perspective view showing one corner of the crib frame and one of 55 the pivoted corner standards.

Fig. 8 is a similar view showing the manner of connecting the frame sections and of holding them against relative movement.

Fig. 9 is a detail perspective view showing 60 the hinge connection of the frame sections on the side opposite to that shown in Fig. 8.

Fig. 10 is an end view of the crib illustrating the manner of securing the same 65 to a bed, the leg for supporting the opposite side of the crib being shown partly in section.

Fig. 11 is a detail perspective view of the clamp used for connection to a bed.

Fig. 12 is a similar view of an auxiliary 70 clamp.

Fig. 13 is a perspective view showing the crib folded and packed in a case for transportation.

Referring to the drawings in detail, 75 wherein like characters of reference denote corresponding parts, the crib is shown as comprising a metal frame which is divided transversely to provide separate sections 15, which are connected together by means of 80 hinges 16 so as to permit them to be folded one upon the other. The frame sections 15 are preferably formed of angle iron and are of substantially U-shaped formation and are held against accidental folding through the 85 medium of a latch 17, which is pivotally mounted as at 18 upon one of the frame sections 15. This latch is engageable with a keeper 19 which is carried by the other frame section so that the latch extends across 90 the joint between the sections upon the side of the frame opposite the hinge 16. One of these latches is preferably provided upon each side of the frame.

Secured within the frame is a bottom 20, 95 which is preferably formed of canvas or other cloth and in order to permit of the removal of this bottom so that it may be laundered, it is removably secured to the frame. The bottom 20 is preferably formed 100 of a plurality of thicknesses of material, one thickness extending over the edges of the other thickness so as to provide flaps 21, which overlie springs 22. One end of these springs are connected within gromets 23 and 105 have their opposite ends connected in open-

ings provided in the frame. The corner springs have their opposite ends secured within openings formed in corner braces 24.

The crib is further provided with washable side and end walls 25 and 26 respectively. These side and end walls are preferably formed from a single strip of canvas or similar material, and are detachably connected to corner standards 27 and side standards 27^a. The corner standards 27 are pivotally secured to the frame so that they may be folded downward the direction indicated by the dotted lines in Fig. 7, until they lie flush with the sides of the frame. They are held in upright position through the medium of latches 28, which are pivotally connected as at 29 to the frame and have their outer ends provided with shoulders 30 for engagement with the standards 27 as also illustrated in Fig. 7. Pins 31 serve to limit the movement of the latches 28 in one direction, while other pins 32 limit the movement of these latches in an opposite direction, the purpose being to confine the latches within the width of the frame when the latter is folded. The side standards 27^a are also pivotally connected to the frame as illustrated at 33, but upon one side of the frame and slightly spaced from the standards 27^a is an additional standard 27^b, also pivotally secured to the frame and like the standards 27^a is capable of being folded downward parallel with the frame. Its upper end is detachably connected to the standard 27^b at its upper end by means of a link 34. The canvas strip which forms the side and end walls is provided with openings suitably spaced apart and extending from the standards for passage through these openings are threaded lugs 35, which are engaged by thumb nuts 36 and thus removably hold the side and end walls in position.

To fold the crib as is illustrated in Fig. 5, the side walls 25 are detached from the standard 27^a, which will permit standards 27 to be swung downwardly, such movement will lap or cause side walls 26 to be doubled upon themselves, and to be brought into engagement with the bottom 20. The side walls are then overlapped as is illustrated in Fig. 5.

The ends of the strip of which the walls are formed overlap upon one side of the crib as shown at 37 and if desired the ends of the strip which form this wall may be folded backward against the end walls 26 to provide an open side for the crib, so that the latter may be placed alongside of the bed and the occupant of the crib be within convenient reach.

The crib may be supported upon the bed, or it may be independently supported and for the latter purpose there is provided legs 38. These legs are located at opposite ends

of the crib and are preferably formed of heavy wire. As shown, they are U-shaped and their ends extend outwardly to provide pivots 39 which engage openings formed in the frame. When the crib is folded these legs fold upward beneath the sections 15 within the frame.

In order to support the crib upon the bed there is provided clamps 39. One of these clamps is removably secured at each end of the bed and projects laterally from one side as shown in Fig. 10. They include L-shaped bars 40, one end of which is removably connected to the frame as at 41, while the opposite end of the L-shaped bars are provided with spaced openings 42. This last mentioned end of the bar 40 has removably and adjustably secured thereto a substantially U-shaped hook 43 which is adapted to engage beneath the side bar 44 of the bed frame, as shown in Fig. 10 and to be held in such engaged position through the medium of a set screw 45. The hook 43 is provided with a stud 46 for engagement in one of the openings 42, while a set screw 47 passes through one of these openings for engagement with a threaded opening provided in an extension 48 of the U-shaped member 43. This U-shaped member may thus be adjustably positioned upon the member 40 so that the latter will rest upon the upper edge of the side bar 44 of the bed, as also shown in Fig. 10.

In order to support the opposite side of the crib there is provided an extensible leg 49. This leg comprises sections 50 and 51, the inner end of the first mentioned section being pivotally secured to the frame, while the outer end carries a stud 52 for engagement in any one of a number of spaced openings 53 provided in the section 51. A set screw 54 also passes through the openings 53 and engages a threaded opening provided in the section 50. This provides for regulating the length of the leg 49 in accordance with the height of the bed to which the crib is attached and at the same time permitting said leg to be folded upward out of the way when not in use, as shown in Fig. 1 of the drawings. The lower end of the leg 51 carries a caster 55. For the purpose of bracing the leg 49 there is provided brace bars 56, one end of which is pivotally secured to the frame upon the opposite sides of the hinged connection of the sections 15 as shown at 57, while the opposite ends of these bars 56 are provided with notches 58 for engagement over a pin 59 carries by the leg section 50. This permits the leg to be folded upward parallel with the frame when the crib is folded.

In Fig. 12 there is illustrated an auxiliary clamping hook 60, which may be engaged with a convenient portion of the bed, for example, with the side bars of the bed

spring. This hook is provided with a threaded extremity 61, at the inner end of which is located a stop 62. The threaded extremity 61 is adapted for passage through 5 one of the openings 42 of the member 40 and is limited in its movement in one direction by a shoulder 62, while a thumb nut 63 provides a clamp upon the opposite side of the member 40 and acts to hold the hook 60 10 securely in position.

By forming the bottom and side and end walls of washable material and attaching them in the manner shown, they may be conveniently removed and washed and the 15 crib kept in a sanitary condition. In addition, the crib is so constructed as to permit of its being quickly and compactly folded into a small space. In folding, the end walls 26 are first folded inward and the side walls 20 folded over the end walls so as to occupy the position shown in Fig. 5 of the drawings. The latches 17 are then released and the action of the springs 22 will break the joint of the frame sections connected by the hinges 25 16 and the sections may then be folded one upon the other with the side and end walls 25 and 26 inside. The legs 38 and 49 are also folded so that the crib will be arranged as illustrated in Fig. 6 of the drawings, 30 whereupon, the legs 38 may be connected by hooks 64 carried by one of the legs and accidental unfolding of the crib prevented. If desired, the crib may be arranged within a casing 65, as illustrated in Fig. 13 and may 35 thus be conveniently carried.

The invention is susceptible of various changes in its form, proportions and minor details of construction and the right is herein reserved to make such changes as properly

fall within the scope of the appended 40 claims.

Having described the invention what is claimed is:—

1. A folding crib comprising a frame formed in separate sections and hingedly secured together, means for preventing the sections from folding, foldable supporting legs connected to the frame, a foldable bottom, side and end walls secured to the frame, means for supporting the foldable side and end walls, said means including pivotally mounted standards and means engageable with the standards for holding the latter in upright position. 45

2. A folding cot comprising a frame 55 formed in separate sections and hingedly secured together, means for preventing the sections from folding, foldable supporting legs connected to the frame, a foldable bottom, side and end walls secured to the frame, means for supporting the foldable side and end walls, said means including pivotally mounted standards and latches pivotally secured to the frame and provided with shoulders engageable with the standards for holding the latter in upright position. 60

3. A cot embodying a frame, bottom, side and end walls of washable material, means for detachably securing the bottom to the frame, standards secured to the frame, lugs 70 projecting from the standards for engagement in openings formed in the side and end walls and means engageable with the lugs for detachably holding the side and end walls in position. 75

I testimony whereof I affix my signature.

HARRY CHAS. McCORD.
